UNITED STATES PATENT OFFICE.

HERMANN ARON, OF CHARLOTTENBURG, GERMANY.

ELECTRIC METER.

SPECIFICATION forming part of Letters Patent No. 701,280, dated June 3, 1902.

Application filed February 20, 1902. Serial No. 94,898. (No model.)

To all whom it may concern:

Be it known that I, HERMANN ARON, a subject of the King of Prussia, German Emperor, residing at No. 39 Wilmersdorferstrasse, 5 Charlottenburg, in the Kingdom of Prussia, German Empire, have invented certain new and useful Improvements in Electric Meters, (for which I have made application for Letters Patent in Germany, dated January 14, 10 1901, Serial No. A. 7,684,) of which the following is a specification.

The meter to which my invention relates is of that type in which the current is delivered by the meter for a predetermined period of 15 time, the period of delivery being determined by a clockwork mechanism which is set to run for a certain period of time, during which the current will be delivered through the meter, and at the end of which period the said 20 clockwork mechanism will automatically operate a cut-out device which will prevent further delivery of the current until the mechanism has been again set for delivery of current during another period of time. Apparatus of this kind, generally speaking, is not 25 new and has been heretofore employed.

The main features of my invention consist in employing a planet-wheel gearing which determines the length of time of delivery of 30 the current and a second planet-wheel gearing, which drives the clock mechanism and also operates the cut-out device to interrupt the circuit when the period of time for which the first-named planet-wheel gearing mechanism was set during which current will be 35 delivered has elapsed. Planet-wheel gearing has been employed before for determining the period of delivery of an electric current and also for operating the cut-out device in meters; but the present mechanism has the advantage over those heretofore known to me in that a single driving mechanism controls the whole work of operating the metering devices and the cut-out mechanism, while a further advantage of the present construction is that the mechanism which 40 determines the period of delivery is returned to its original position after having been set by a uniform continuous motion and does 45 not return to its normal position by sudden steps or intervals, as in certain mechanisms 50

now in use, which method of operation frequently causes undue deviations in the operation of the meter.

In the accompanying drawings I have 55 shown so much of the meter as relates to my improvements, indicating in dotted lines the parts of the clock mechanism which do not relate to the particular means herein set up and claimed as of my invention, and in said 60 drawings—

Figure 1 is a side view in elevation of the planet-wheel mechanism and its connected parts which control or determine the period of delivery of the current and also release 65 the cut-out device. Fig. 2 is a front elevation looking from the left in Fig. 1, the side plate of the frame being removed and the clockwork mechanism being illustrated in dotted lines. Fig. 3 is a view similar to Fig. 70 2, showing the cut-out-controlling device in reverse position from that shown in Fig. 1. Fig. 4 is a view in side elevation of the planet-wheel gearing which controls and drives the clockwork mechanism and the cut-out device 75 and the electrical driving mechanism which imparts motion to the said planet-wheel gearing. Fig. 5 is a side elevation of the mechanism for braking the clockwork.

Referring to the drawings by letters, the 80 same letters indicating like parts in the several views, *k* denotes what may be termed the “setting-wheel” of the meter, for the reason that the rotation of this wheel, which is effected manually and preferably through the 85 intervention of any suitable coin-operated or coin-released mechanism, imparts to the planet-wheel gearing which controls and determines the period of time during which the current will be delivered a determinate movement. The said wheel *k* effects this movement of the planet-wheel gearing through a gear-wheel *k'*, which gears with a crown-wheel *g*, mounted on a suitable shaft, said crown-wheel imparting motion to a second crown-wheel *h* through the planet-wheel *i*, as shown 90 in Fig. 1. Each revolution of the wheel *k* will through the gearing just described rotate said crown-wheel *h* through a certain portion of its circumference, and the movements 95 100 of the said crown-wheel will in turn be imparted to the train of gearing (shown in dotted

lines in Fig. 2) in order to set the said train of gearing, the clock mechanism, and the registering devices in proper position for controlling and metering the flow of current. The 5 said crown-wheel *h* is provided with a disk, as shown in Figs. 1, 2, and 3, said disk having thereon a projection *m*. Said projection *m* normally engages a pin *n* on a cut-out-controlling lever *o* and holds it in the position 10 shown in Fig. 2, with the hook *s* of one of the divergent arms of said lever *o* engaging the pin *r* on a disk carried by the cut-out shaft *p*. In this position the cut-out device, which 15 consists of a copper cylinder *q*, having its end *cut away*, as shown in Figs. 4 and 5, will be held in position to interrupt the circuit, one of the brushes *q'* which controls the circuit lying within the cut-away portion of the cylinder *q* and out of contact therewith, so as 20 to break the circuit, and at the same time a pin *v* on a gear-wheel *u*, carried by the cut-out shaft *p*, will bear against a spring *x* and hold a brake *w* pressed against the balance-wheel *y* of the clock mechanism, thus preventing 25 operation of the clock mechanism when the parts are in this position. Upon rotation of the wheel *k* in the manner heretofore described the crown-wheel *h* will be advanced a portion of its circumference in the 30 direction of the arrow, Figs. 2 and 3, to a position such, for example, as is shown in Fig. 3, the pin *n* on the lever *o* being released from the projection *m* and being immediately thrown to the position shown in Fig. 3 by 35 means of a torsional spring *l*, mounted on the supporting-shaft of said lever and shown in Figs. 1 and 4. Said movement of the lever *o* will disengage the hook *s* from the pin *r* on the cut-out shaft *p* and leave the wheel *u* on 40 shaft *p* free to turn under the influence of the second planet-wheel gearing, which constitutes the driving mechanism for the clock-work and which will now be described, this release of the said cut-out shaft *p* permitting 45 it to rotate to the position shown in Fig. 3, with the pin *r* resting against the hook *t* of the other divergent arm of the lever *o*. In this position the cut-out cylinder *q* will contact with both brushes *q' q* and close the circuit, while the pin *v* being removed from contact with the spring-arm *x* the balance-wheel 50 *y* will be relieved of the pressure of brake *w*. The said clockwork - driving planet - wheel gearing comprises the crown-wheel *e*, loosely 55 mounted on a shaft *d*, a planet-wheel *j*, fixed to the shaft *d*, and a second crown-wheel *f*, loosely mounted on the said shaft *d*. The said shaft *d* is connected in any suitable manner to the driving shaft *c* of the electrical driving device, 60 which may be of any known kind and is conventionally shown in the present case, *a* indicating one of the magnet-poles, while *b* indicates an energized coil. (See Fig. 4.) Motion imparted to the shaft *c* by the said electrical 65 driving mechanism will be transmitted

to the shaft *d* and through the planet-wheel *j* imparted to the two crown-wheels *e* and *f*. The crown-wheel *e* gears with the wheel *u* on the cut-out shaft *p*, and when said cut-out shaft has been released through the action 70 of the lever *o*, just described, the said crown-wheel *e* will rotate said shaft slowly, while the crown-wheel *f*, which, as shown in Fig. 2, engages the escapement mechanism of the clockwork, will impart motion to the clock-train. When the parts have been brought to the position shown in Fig. 3, the cut-out device *q*, as has been explained, is in the position shown in Figs. 1 and 5, with the brushes *q'* contacting therewith, and the circuit being 75 closed the electrical driving mechanism will be operated by the current to drive the clock-work. The clockwork will then begin to return the setting mechanism, comprising the crown-wheel *h*, the planet-wheel *i*, and the 80 crown-wheel *g*, to its original position, as shown in Fig. 2, from which it was moved by the rotation of the setting-wheel *k* to the position shown in Fig. 3, and during this period of return movement of the setting mechanism the circuit will be closed, the current will flow through the meter, and the metering and registering devices will be active. This condition will continue until the crown-wheel *h* has been brought to its original position, and the projection *m* on the crown-wheel disk bearing against the pin *n* forces the lever *o* into its normal position, as shown 85 in Fig. 1. This movement of the lever *o* will disengage the hook *t* on the other divergent arm of said lever *o* from the pin *r*, and the cut-out shaft *p* will under the action of the crown-wheel *e* on the driving-shaft *d* be immediately thrown to the position shown in 90 Fig. 1 with the pin *r* engaging the hook *s* and the cut-out device *q* in open-circuit position, thus cutting off the current, applying the brake *w* to the clock mechanism, and arresting the operation of the meter and the delivery of current by it, which condition 95 will exist until the setting-wheel *k* has been again rotated to bring the parts to active position.

I claim—

1. In an electric meter, the combination 115 with a driving-shaft; of a planet-wheel gearing connected with said driving-shaft; a clock-train to actuate the registering devices driven by one of the crown-wheels of said planet-wheel gearing; and a cut-out shaft to 120 open and close the circuit driven by the other crown-wheel of said planet-wheel gearing.
2. In an electric meter, the combination 125 with a driving-shaft; of a planet-wheel gearing connected with said driving-shaft; a clock-train to actuate the registering devices driven by one of the crown-wheels of said planet-wheel gearing; a cut-out shaft to open 130 and close the circuit driven by the other crown-wheel of said planet-wheel gearing; a

second planet-wheel gearing having one crown-wheel driven by said clock-train; and connections between the other crown-wheel of said last-named planet-wheel gearing and the said cut-out shaft, whereby the movements of said shaft are controlled by said crown-wheel.

In witness whereof I have hereunto set my hand in presence of two witnesses.

HERMANN ARON.
